UNITED STATES PATENT OFFICE

2,502,471

DIE LUBRICATING APPARATUS

Edwin J. McIlvried, Cuyahoga Falls, Ohio, assignor to The Vaughn Machinery Company, Cuyahoga Falls, Ohio, a corporation of Ohio

Application December 5, 1945, Serial No. 632,919

4 Claims. (Cl. 205—25)

1

The present improvements relating as indicated to die lubricating apparatus have more particular regard to the lubrication of dies for drawing wire or like elongated metallic articles.

As is well known, in the drawing of wire, it is desirable, in fact necessary, that lubricant should be supplied to the latter at the point where it passes through the die to prevent over-heating both of the die and of the article being drawn. The usual practice has been to spray or squirt the lubricant from above or one side into the die opening or onto the wire as it enters the same, such method requiring the employment of supply conduits which clutter up the draw bench and obstruct the work. Also, such method, in order to insure the desired result, requires the use of a considerable excess of the lubricant.

Accordingly, one principal object of the present invention is to provide a simple and compact form of device for conducting the lubricant to a drawing die and which will be disposed so as to be entirely out of the way, i. e. permit unobstructed observation of and access to the drawing operation. At the same time such lubricating device is adapted to serve the further purpose of holding the die in place in its seat.

To the accomplishment of the foregoing and related ends, said invention then consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:

Fig. 1 is partly a side elevation and partly a section of a typical draw bench equipped with my improved die mechanism; and

Fig. 2 is a transverse vertical section of the same taken on the plane of the line 2—2' on Fig. 1.

As indicated, the draw bench illustrated in the several figures of the drawing is to be taken as representative of any well known type of drawing mechanism for drawing elongated metallic articles. The one selected for illustration is that wherein a plurality of drums or capstans 1 are disposed in alignment, the wire W being passed around successive capstans a sufficient number of times to be frictionally engaged thereby and so capable of being drawn through dies 2 (one only of which is shown) that are suitably mounted between successive capstans. The latter are

2

mounted on spindles 3 journaled in a support 4 which, as shown, forms the back wall of a trough-like frame 5 of the draw bench, such spindles and the corresponding capstans being individually driven.

The die 2, as shown, is in the form of a disc and will be made of the usual hardened steel or other material employed for the purpose, such die having a central flaring opening 6, the larger diameter of which is directed toward the entering wire W as shown in Fig. 1. Each such die is supported in proper position by being seated in a corresponding circular recess 7 formed in an up-standing bracket 8 that rises from the floor of the trough-like frame member 5, said bracket being laterally cut away so as not to interfere with the free passage of the wire through the die from one capstan to the next. Also as shown in Fig. 2 a continuous unobstructed space is left between the brackets and the front wall 9 of said trough-like frame member.

The latter is furthermore formed so as to provide beneath the trough in question a continuous longitudinally extending chamber 10, only the upper portion of which appears in the several figures of the drawing, such chamber being closed off and provided with means for supplying thereto under desired pressure the lubricant which it is desired in turn to supply to the respective dies 2. It will be understood that the lubricant thus employed, whether it be an oil or one of the special compositions employed for the purpose, will be sufficiently fluid in character so that under pressure it may be caused to flow in the manner which will be presently described as involved in the operation of the apparatus.

The upper wall of chamber 10 is formed with a longitudinally extending slot 11 which is aligned with the axes of the series of dies 2 when seated, 40 in the manner previously described, in their respective supporting brackets 8, and, adjacent each such bracket, such wall is further formed with a circular bore 12 disposed at an angle so as to incline toward such bracket and the die 2 when seated therein. The lower portion of bore 12 extends downwardly into but not entirely through the slot 11, a continuation 13 of such bore of smaller diameter serving to connect the same with the chamber 10. Reciprocably held in bore 12 is a tubular member 14, a compression spring 15 being interposed between the lower end thereof and the lower end of such bore where a shoulder is provided by reason of the smaller diameter of the continuation 13 of the latter. A stud, preferably in the form of a set screw 16 as shown, is

secured to the lower side of said tubular member 14, such stud by its engagement with slot 11 serving to hold said member against rotation in the bore.

The side 17 of the upper end of tubular member 14 which is opposed to die 2 is cut back on a vertical plane so as to present a flat arcuate face 17 to such die where such end contacts with the latter. The opposite side of such end is formed with a notch 18 so as to provide ample clearance for the wire W as it enters the opening 6 in the die.

Having now described the construction of my improved lubricating apparatus, the manner of its operation will be briefly set forth.

Assuming the chamber 10 is charged with lubricant under the proper degree of pressure, such lubricant will flow or well through the extension 13 of bore 12, thence through the compression spring 15 and tubular member 14, from the upper end of which it will be supplied directly to the flaring end of die opening 6. The notch 18 will preferably be slightly higher than the lower point of the arcuate face 17 of the tubular member that is pressed against the die, so that the natural tendency of the lubricant, supplemented by the dragging action of the wire, will be to cause the same to flow into and through the die. It will thus be seen that the lubricant is supplied exactly at the point where it is required and that very little excess amount of such lubricant will be needed, all the splashing and mess that are incidental to present methods of die lubrication being eliminated. Such excess as there may be will, of course, be collected in the trough and can be returned for use or other disposal as desired.

As previously indicated, tubular member 14 at the same time that it serves to conduct lubricant to the die acts also as a retainer for the latter whereby it is held against accidental dislodgement from its seat in bracket 8. However, should it be desired to remove the die for replacement or other purpose, this can be readily accomplished by simply pressing member 14 against spring 15. The stud 16 will normally prevent the dislodgement of member 14 from the bore when the die is thus removed, as well as retain said member in proper axial position so that its upper end will contact with the die in the manner previously described. However, by removing stud 16, the member 14 as well as spring 15 will be rendered entirely free for the purpose of disassembly of the apparatus.

From the foregoing it will be seen that I have provided at the same time an extremely simple and yet highly efficient apparatus for lubricating the dies in a draw-bench. While the construction of such apparatus particularly lends itself to the type of draw-bench in which an aligned series of dies is utilized, the novel features of construction may of course be equally well utilized in connection with an individually mounted die.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In a die retaining and lubricating apparatus, the combination of a support providing a die seat, a die in such seat, a retainer formed with a passage for supplying lubricant to said die, means supporting said retainer for movement toward and away from said die, and spring means urging said retainer into engagement with said die for exerting pressure on said die for holding it in such seat.

2. In a die retaining and lubricating apparatus, the combination of a support providing a vertically disposed die seat, a die in such seat, a retainer inclined upwardly toward said die and formed with a passage for supplying lubricant to said die, means supporting said retainer for movement toward and away from said die, and spring means urging said retainer into engagement with said die for exerting pressure on said die for holding it in such seat.

3. In a die retaining and lubricating apparatus, the combination of a support providing a vertically disposed die seat, a die in such seat, a tubular retainer inclined upwardly toward said die, guide means provided with a bore slidably receiving said retainer for movement toward and away from said die, spring means urging said retainer into engagement with said die for exerting pressure on said die for holding it in such seat, and inter-engaging means on said retainer and guide means rendering said retainer non-rotatable in such bore.

4. In a die retaining and lubricating apparatus, the combination of a support providing a vertically disposed die seat, a die in such seat, a tubular retainer inclined upwardly toward said die, guide means provided with a bore slidably receiving said retainer for movement toward and away from said die, spring means urging said retainer into engagement with said die for exerting pressure on said die for holding it in such seat, and inter-engaging means on said retainer and guide means rendering said retainer non-rotatable in such bore, said retainer being formed with a vertically disposed face in engagement with said die.

EDWIN J. McILVRIED.
